UNITED STATES PATENT OFFICE.

GUSTAV A. FAITZ, OF CHICAGO, ILLINOIS.

CAR-JOURNAL-BOX COVER.

No. 824,850.

Specification of Letters Patent.

Patented July 3, 1906.

Application filed February 11, 1904. Serial No. 193,042.

To all whom it may concern:

Be it known that I, GUSTAV A. FAITZ, a citizen of the United States, and a resident of Chicago, Cook county, Illinois, have invented 5 certain new and useful Improvements in Car-Journal-Box Covers; and I do hereby declare that the following is a full, clear, and exact description of the same, reference being had to the accompanying drawings, and to the 10 letters of reference marked thereon, which form a part of this specification.

This invention relates to improvements in car-journal-box covers or car-axle boxes and is shown applied to a journal-box of the Master Car-Builders' type.

Heretofore it has been difficult to provide a journal-box cover adapted to facilitate inspection of the contents of the journal-box for the purpose of supplying lubricant there- 20 to or for purposes of repair, which, though permitting such inspection, also acts to entirely exclude dust, dirt, and cinders from finding access to the journal through the outer end of the box. In many of the de- 25 vices heretofore constructed for the purpose the cover has not only permitted dirt to find its way into the journal-box, but in many instances the covers are so attached to the box as to become readily detached, thus leaving 30 the entire end of the box open. Many of such covers are so constructed also as to render inspection difficult, frequently requiring the expenditure of considerable time to open the box to complete the inspection and again 35 close the box.

The object of this invention is to provide a cover construction adapted to be instantaneously opened and to remain supported in an open position during inspection and to be 40 quickly closed, and when closed to absolutely exclude the entry of dust, dirt, or other objectionable material into the box.

The invention embraces many novel features; and it consists of the matters herein- 45 after described, and more fully pointed out and defined in the appended claims.

In the drawings, Figure 1 is a side elevation of a journal-box provided with a journal- 50 box cover embodying my invention. Fig 2 is a front end elevation of the same. Fig. 3 is an enlarged vertical fragmentary section of the end of the journal-box and cover, showing the same closed and showing in dotted lines its open position. Fig. 4 is a front elevation of the cover, showing the inner flange and the carrying-plate in dotted lines. Fig.

5 is a bottom plan view of the cover embodying my invention with the carrying-plate removed. Fig. 6 is a fragmentary view and is similar to that shown in Fig. 3, but illustrates a construction in which the pintle is omitted. Fig. 7 is a section taken on line 77 of Fig. 6. Fig. 8 is a central section of a slightly-modified construction of the connection between the cover and the carrying- 65 plate. Fig. 9 is a fragmentary top plan view of the cover, showing the stem connecting the carrying-plate with the cover in section.

As shown in said drawings, A indicates a journal-box of the usual or Master Car-Builders' type provided at its top and outer end with an outwardly and upwardly extended lug *a*, on which is pivotally supported the cover embracing my invention. Said cover comprises a cover B of a size adapted to cover 70 and overlap the sides and top and bottom of the open end of the journal-box and provided on its inner face with a flange *b*, which fits closely in the open end of said journal-box and acts to hold said plate in register with 75 said opening. Said cover B may be of any desired material. As shown, however, and conveniently, the same is of malleable iron or other suitable metal and is provided, as shown in Figs. 1 to 5, inclusive, on its outer 80 face with a central ball-shaped depression, surrounded with a plurality of outwardly-directed prongs or projections *b'*, adapted to receive between the same and in said depression the ball-shaped head *C* of the pin *c*, 85 whereby the carrying-plate D is movably connected therewith. The points or projections *b'* are closed down over the head *C* of said pin, affording a ball-and-socket joint, and said pin projects through an aperture in the 90 carrying-plate D and is closed down thereon by riveting or in any suitable means permanently connecting the cover B with said carrying-plate D, though permitting considerable relative movement.

The carrying-plate, as shown, is provided at its upper end with a recessed knuckle *d*, adapted to extend over the projection *a* on the box and is provided with a transverse aperture adapted to receive a pintle *a'*, whereby 105 the same is hinged to said projection. Said carrying-plate, as shown, is cored out to afford an interior recess for approximately its entire length, but which terminates near the pin *c* in a pocket or recess adapted to receive 110 the lower end of a strong leaf-spring *d'*. The upper end of said spring bears upon the for-

wardly-extended end of the projection of *a*, the outer under side of which affords a cam which holds the end of the leaf-spring under compression and sufficiently beyond the 5 hinge to jam the cover firmly against the open end of the box, thereby holding the cover firmly closed. The upper surface of said projection *a* on the box is also shaped to afford a cam-surface, so that when the cover 10 is elevated, as shown in dotted lines in Figs. 3 and 6, the upper end of the leaf-spring lies along the top of the projection *a* and supports the cover, leaving the end of the box open for inspection or lubrication.

15 As shown, a vertical rib *b*² is provided on each side of the center of the cover on the outer side and above the pin. Said ribs fit closely in the recess in the carrying-plate, as shown in dotted lines, Fig. 4, and act to hold

20 the cover from turning on the pivotal connection between the same and the carrying-plate afforded by the pin *c*. If preferred, the connection of the cover and the carrying-plate may be afforded by means of a ball-shaped

25 connecting member *C'*, provided with a pin *c*³, adapted for connection with the carrying-plate, as before described, and the ball-shaped end of which may be inserted into the mold at the time the cover is cast, thereby permitting

30 the same to be cast into the cover-plate, as shown in Figs. 8 and 9, thus affording a permanent though flexible connection between the cover and the carrying-plate. If preferred, the pintle *a'* may be omitted, and

35 an inwardly-directed lug *d*³ is cast or otherwise provided at the top of the carrying-plate, and a downwardly-inclined recess is provided in each side of the projection *a*, as shown in Fig. 6, adapted to receive said lugs. With

40 this construction a shoulder *d*⁴ may conveniently be provided near the upper surface and back of the projection *a*, against which the end of the leaf-spring *d*² engages when the cover is elevated, as shown in Fig. 6, thus

45 holding the cover-plate from being detached accidentally when the cover is raised.

The operation is as follows: The pressure of the spring *d*² on the forwardly-extending end of the projection *a* acts to hold the cover 50 either in its closed or its open position. This will be seen from reference to Fig. 3, in which the forwardly-extending point of said projection of *a* bears the upper end of the spring away from the pivot, bringing sufficient tension thereon to force the lower end of the carrying-plate, with the cover attached thereto, into firm bearing against the open end of the box. Should, however, the cover be elevated, the end of said spring engages along 55 the top of the projection *a*, the extended point thereof affording a support. The resistance of said spring is sufficient to support the cover in its open position.

Owing to the construction described it is 60 obvious that when the cover is thrown down

to its closed position it is brought invariably into exact register with the opening in the end of the box, the ribs *b* fitting therein closely and affording a joint sufficiently tight to exclude dust or dirt. The connection between the cover and the carrying-plate being such as to afford a ball-and-socket joint enables the cover to adapt itself 70 perfectly to the opening in the journal-box independently of any slight variance in the point of pivotal attachment of the carrying-plate with the journal-box. Inasmuch, too, as the point of the connection of the carrying-plate with the cover is at the center of the latter the pressure of the spring is exerted equally in all directions on said cover, 75 acting to hold the same firmly in position with equal pressure on all sides of the box-opening.

I claim as my invention—

1. In a car-journal-box cover adapted to entirely close the open end of the box, a cover-plate, a carrying-plate hinged to the box, means adapted to hold the cover-plate in register with the box comprising a recess 90 in the under side of said carrying-plate, adapted to receive an outwardly-directed flange on the cover-plate and a ball carried on said carrying-plate, there being a socket on said cover-plate adapted to closely engage about said ball. 95

2. In a cover for a journal-box, a cover-plate provided with a continuous inner flange to fit within the open end of the journal-box, a carrying member on said box provided 100 with a recess on its under side adapted to receive flanges on said cover-plate, a spring in said recess adapted to normally hold the cover-plate closed, a pin rigidly engaged in said carrying member and provided with a 105 ball-shaped head, there being means on the cover-plate adapted to closely engage over the top of said ball and together therewith form a ball-and-socket joint.

3. A car-journal-box cover comprising a 110 cover-plate provided with an internal continuous flange adapted to fit closely in the open end of the box and positioned at a distance from the margin of the cover, a carrying-plate hinged on the box and provided 115 with depending lateral flanges and a recess intermediate said flanges, there being integral outwardly-directed flanges on said cover-plate adapted to engage in the flanges on said carrying-plate and means flexibly 120 engaging said plates together.

4. A cover for car journal-boxes comprising a cover-plate provided with a continuous internal flange adapted to fit closely in the open end of the box, a carrying-plate 125 hinged on the box and provided with inwardly-directed lateral flanges adapted to engage complementary flanges on the cover-plate, a ball rigidly engaged on said carrying-plate, there being a socket in said cover- 130

plate adapted to fit closely about said ball and a spring carried beneath said carrying-plate acting to hold the cover-plate in its open or closed position.

5. A cover for car journal-boxes comprising a cover-plate having an internal continuous flange on the inner side thereof adjacent its margins adapted to fit within the journal-box and parallel flanges on the outer side of the cover-plate, on opposite sides of the center, a carrying-plate hinged on the journal-box and centrally on said cover-plate and having a recess therein adapted to receive and to secure said flanges and a spring acting 10 to support the cover when open and to hold the same in position when closed.

6. In a device of the class described the combination with a journal-box having a projection above the opening thereof provided with upper and lower cam-surfaces 15

and having slots in the sides thereof, a carrying-plate having a recessed knuckle thereon adapted to receive said projection, inwardly-directed pintles thereon adapted to engage in said slots a leaf-spring carried in 20 said plate and adapted to normally engage the lower cam-surface under tension when the plate is in its lowermost position, and to engage the upper cam-surface when in its uppermost position, a cover-plate and means 25 providing a flexible joint between the same and the carrying-plate.

In testimony whereof I have hereunto subscribed my name in the presence of two subscribing witnesses.
